UNITED STATES PATENT OFFICE

120,143

DESIGN FOR A DISPLAY CABINET

Lowell W. Shields, Rochester, N. Y., assignor to Hickok Manufacturing Company, Inc., Rochester,
N. Y., a corporation of New York

Application February 5, 1940, Serial No. 90,052

Term of patent 7 years

To all whom it may concern:

Be it known that I, Lowell W. Shields, a citizen of the United States, residing at Rochester, in the county of Monroe and State of New York, have invented a new, original, and ornamental Design for Display Cabinets, of which the following is a specification, reference being had to the accompanying drawing, forming part thereof.

In the drawing:

I claim:

The ornamental design for a display cabinet, substantially as shown.

LOWELL W. SHIELDS.
